UNITED STATES PATENT OFFICE.

SIMEON G. PHILLIPS, OF WOODBRIDGE, NEW JERSEY.

DRYING APPARATUS.

SPECIFICATION forming part of Letters Patent No. 449,231, dated March 31, 1891.

Application filed September 11, 1890. Serial No. 364,684. (No model.)

To all whom it may concern:

Be it known that I, SIMEON G. PHILLIPS, a citizen of the United States, residing at Woodbridge, in the county of Middlesex, in the 5 State of New Jersey, have invented a certain new and useful Improvement in Drying Apparatus, of which the following is a specification.

The invention is intended more especially for drying bricks, and will be described as thus applied; but it may be successfully used in drying lumber and various articles which can be similarly piled in open-work form on cars or analogous carriers. I traverse the 10 material slowly through a building or large chamber, moving it either continuously or intermittently and subjecting it to lateral currents of air artificially warmed and peculiarly conditioned and economize the heat and in- 15 duce uniform and just sufficiently rapid drying. Successfully drying bricks requires considerable time, as the surface is likely to "check" if it is hastened beyond a certain point. In what I esteem the most complete 20 form of the invention there are a number of screw-fans urging the air laterally across the building and a number of narrow-gage railway-tracks provided with narrow cars or carriers traversed thereon in lines longitudinal 25 of the building. A liberal current of air is taken in cold at one end and is warmed in part by the heat of the bricks which are about to be discharged, thus utilizing the heat and cooling the bricks. The air is further warmed 30 by steam-pipes arranged in the route and the temperature is raised as the air traverses suc- 35 cessively across the several tracks and through the spaces between the bricks on the several carriers or cars. I so arrange the apparatus 40 that the air shall traverse several times across, returning above or below the drying-room. In the last part of its course no more heat is imparted to it, but the warmed air loaded with moisture is useful mainly in warming 45 the bricks entering the apparatus. The air taken in cold and dry is discharged nearly as cold, but loaded with moisture. All the heat 50 is utilized, and at no point is any of the material dried so fast as to be injured. In ordi- 55 nary conditions of the atmosphere it re- 60 quires from a few hours to a few days to carry the material through the building or chamber.

The rate of travel on any particular track or on all the tracks should be controlled by the attendants as is found expedient under the 55 conditions.

The accompanying drawings form a part of this specification and represent what I consider the best means of carrying out the invention. 60

Figure 1 is a horizontal section. Fig. 2 is an end elevation. Fig. 3 is a cross-section on the line *x* *x* in Fig. 1. Fig. 4 is an elevation of a portion on a larger scale.

Similar letters of reference indicate corresponding parts in all the figures where they appear. 65

A is the building, which may be about seventy-five feet long and forty wide in a single room, except as hereinafter described. The 70 top is formed by a partial ceiling A², giving a nearly-uniform height of six feet or other convenient height. Seven narrow-gage railroad-tracks B extend in parallel and nearly-equally spaced lines the length of the interior, carrying single-deck or double-deck cars B' of the style commonly used in drying bricks. It is especially important in my system that there be no sides or partial sides to these cars, and the bricks in being placed 80 thereon should be piled to allow a circulation of air transversely across instead of longitudinally along the several loads. The piles of brick are arranged rectangularly, and extend upward so as to nearly touch the partial 85 ceiling, and longitudinally so that each load nearly touches the corresponding rectangular load on the next car.

D D are screw-fans arranged in sets between the tracks and adapted to propel the 90 air transversely to the track, allowing it to return through liberal passages provided above the ceiling or partial flooring A².

Convenient doors allow the cars on the several tracks to be entered and removed. The 95 cars enter with their loads of freshly-made damp bricks at what I may, for example, assume to be the north end of the building, the upper side in Fig. 1, and are slowly traversed southwardly along the several tracks, the motion being usually intermittent, and may vary on the several tracks as the drying 100 shall be found to require.

E are heating-pipes arranged between the

tracks and kept filled with steam. I have in my experiments used mainly exhaust-steam from a steam-engine, but live steam may be admitted, if required, the water of condensation being trapped or otherwise taken out as fast as formed, so as to give as large a heating-surface as possible to warm the air at an early stage of its passage through the building across the several tracks and through the spaces in the several loads of bricks lying in its way. The steam-pipes E extend along the mid-length about half or two-thirds the length of the building. The end where the fresh loads of bricks are received being without any heating means, the heat previously stored in the damp air there being discharged is made use of to warm the fresh bricks, leaving the actual evaporation of the moisture from the bricks to be effected mainly at later stages in the traverse of the several loads of bricks through the building. The air traverses across and back several times, but each time it traverses the drying-room in the same direction, from left to right, returning through liberal passages provided above, as indicated by the arrows in Fig. 3.

The several screw-fans D are mounted on shafts arranged transversely and are driven by quarter-twist belts from lines of shafting above. The fans may be either right-handed or left-handed screws, but rotated in such direction that the air will move across the tracks from left to right. The air is received cold and dry at one end of the building and grows rapidly warm from two causes, the circulating across the several net-works of heating-pipes E, which present surfaces nearly up to steam heat, and the circulating through the spaces between the hot bricks, which are now in the last stages of the drying operation and are about to be discharged from the building.

I esteem it important to utilize the heat in the bricks, and attain this in a good degree by arranging to induct the cold air through the car-loads of bricks about to be discharged, and thus to take into the air a good proportion of the heat in those bricks before bringing the air in contact with the steam-pipes. To this end the steam-pipes do not extend quite to the hot end of the building. I have before stated that a considerable length of the other and cooler end of each track, that at which the air is received, is unprovided with heating-pipes. I am now adding that a short portion of this end, the hot end of each, is also without heating means other than the loads of bricks which are standing there, and which give up their heat to the current of freshly-induced cold dry air being received. The drawings show what I esteem about the best proportion.

The passage of air across in the spaces over the tops of the loads and below the partial flooring is reduced by screens extending downward a foot or more between the lines of cars at the ceiling. The passage of air across un-

der the bodies of the cars is retarded by corresponding screens or fences extending upward from the floor along certain lines.

G G are screens depending from the ceiling or partial flooring A², and H are screens extending upward from the floor. Both sets of screens extend longitudinally between the lines of cars. The screens H are not directly under the screens G.

C C are belts having the proper quarter-twist, which convey the power from suitable pulleys M' on the proper line-shafts M above to the pulleys D' on the shafts of the screw-fans D.

The liberal aperture in the side of the building through which air is inducted is marked a. It may extend about one-third of the length of the building. A corresponding aperture a' at the opposite corner serves for the exit.

The temperature at which the damp fresh bricks enter the building along the several tracks depends on the season of the year and various conditions, one important condition being the mode of their manufacture. While some greatly-compressed bricks come from the machine (not shown) and enter the building at a temperature as high as 90° Fahrenheit, so that it is easy to raise them to 150° Fahrenheit by steam heat alone, there is little need to utilize the last increments of heat in the moisture-laden air. There are other modes of manufacture, eminently what are technically known as "mud bricks," which deliver the bricks cold. There may be seven or any other considerable number of lines of cars, and the air is in all cases blown across through the spaces in the loads of cold bricks in each.

My invention presents the air very thoroughly and evenly to the several loads of bricks and so as to dry them rapidly under favorable conditions, but not so rapidly as to cause the surfaces to check. The air which first strikes the green bricks is warm, but damp. The damp compressed clay thus conditioned rises in temperature simply. As the bricks advance they begin to give off their moisture, meeting, or rather, being traversed laterally by currents of air successively drier as they advance, but always so conditioned that the surface will not check. Just before they emerge they are traversed by freshly-received cold air.

The apparatus requires for its proper management but a small amount of skill or care, the adjustments being mainly automatic. The action of the screw-fans not only impels the air in the required direction, but also throws it into a great number of intermingling currents. The traversing across in this manner is specially adapted to dry fruits and any articles for which the temperature should be moderate.

Modifications may be made without departing from the principle or sacrificing the advantages of the invention. Instead of six

screw-fans in each set I can have a greater or less number. The drawings show partitions extending along parallel to the tracks with the screw-fans worked in apertures about the same size as the fans. The invention may be so worked, but it may be preferable in some cases to omit such longitudinal partitions and allow the air to move as freely as possible, simply aiding its general progress by 10 the fans. I can work successfully by a single set or line of fans, or by any other number of lines with the fans, all impelling the air laterally in the same direction. The air may be returned in corresponding passages (or a sufficient chamber) below instead of above the main room (the drying-room) wherever the elevation of the building and the facilities for drainage, &c., will allow such arrangement. It is practicable to heat the air by 15 other means than steam-pipes—hot-air pipes, or smoke-flues, or any other suitable heating agent may be used.

The invention is not confined to drying bricks. It may be used with much advantage in drying lumber. The screw-fans may be driven by open belts instead of quarter-twist belts, but such require a greater expenditure for counter-shafting.

I claim as my invention—

30 1. In a drying apparatus, the partial ceiling A², heating-pipes E, and means, as the

fan-wheels D, for inducing a current of air transversely under the ceiling in one direction and above the ceiling in another direction, advancing longitudinally toward the end of the apparatus at which the air is discharged, substantially as herein specified. 35

2. In a drying apparatus, the partial ceiling A², heating-pipes E, and means, as the fan-wheels D, for inducing a current of air transversely under the ceiling in one direction and above the ceiling in another direction, advancing longitudinally toward the end of the apparatus at which the air is discharged, in combination with means, as the 40 tracks B and cars B', for traversing the bricks longitudinally of the structure in the opposite direction and transversely to the motion of the air, the heating means being reduced where the air is received, so that it will be 45 partly warmed by the heat in the outgoing bricks, all arranged for joint operation substantially as herein specified. 50

In testimony that I claim the invention above set forth I affix my signature in presence of two witnesses.

SIMEON G. PHILLIPS.
